DRAFTSMAN'S GAGE FOR MEASURING CONICAL ANGLES

Raymond L. Mulvane, South Gate, Calif.

Original application July 19, 1957, Serial No. D. 46,992,
now Patent No. D. 183,627, dated September 30, 1958.
Divided and this application October 2, 1957, Serial
No. 47,941

Term of patent 14 years

(Cl. D52—1)

Fig. 2

Fig. 3

Fig. 4

Fig. 5

Fig. 1 is a plan view of a draftsman's gage for measuring conical angles showing my new design. The side opposite to that shown in Fig. 1 is the same in appearance.

Fig. 2 is a sectional view on line 2—2 of Fig. 1.

Fig. 3 is a sectional view on line 3—3 of Fig. 1.

Fig. 4 is a sectional view on line 4—4 of Fig. 1.

Fig. 5 is a sectional view on line 5—5 of Fig. 1.

This application is a division of my application Serial No. 46,992, filed July 19, 1957.

I claim:

The ornamental design for a draftsman's gage for measuring conical angles, as shown and described.
